US0D1114260S

(12) **United States Design Patent** (10) **Patent No.:** **US D1,114,260 S**
(45) **Date of Patent:** **** Feb. 17, 2026**

(54) **MEDICAL DEVICE**

(71) Applicant: **Welch Allyn, Inc.**, Skaneateles Falls, NY (US)

(72) Inventors: **Howard A. Haines, III**, Auburn, NY (US); **Mary K. Hedden**, Liverpool, NY (US); **Scott W. Osiecki**, Skaneateles Falls, NY (US)

(73) Assignee: **WELCH ALLYN, INC.**, Skaneateless Falls, NY (US)

(**) Term: **15 Years**

(21) Appl. No.: **29/914,413**

(22) Filed: **Oct. 17, 2023**

(51) **LOC (15) Cl.** **24-02**

(52) **U.S. Cl.**

USPC **D24/165**

(58) **Field of Classification Search**

USPC D24/164, 165, 166, 167, 168, 185, 186; D10/70, 75, 78, 104.1; D14/341, 344

CPC A61B 5/00; A61B 5/021; A61B 5/02141; A61B 5/02158; A61B 8/04

CLAIM

The ornamental design for a medical device as shown and described.

DESCRIPTION

FIG. 1 is a perspective view of a medical device showing our new design, shown from the top, front, and right side; FIG. 2 is another perspective view thereof, shown from the top, rear, and left side;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict features of the medical device that form no part of the claimed design.

1 Claim, 6 Drawing Sheets
